UNITED STATES PATENT OFFICE.

EARL W. KEYSER, OF WHEELING, WEST VIRGINIA.

CUTICLE STICK.

1,413,033.

Specification of Letters Patent. Patented Apr. 18, 1922.

Application filed April 6, 1921. Serial No. 453,883.

To all whom it may concern:

Be it known that I, EARL W. KEYSER, a citizen of the United States of America, and resident of Wheeling, county of Ohio, and 5 State of West Virginia, have invented certain new and useful Improvements in Cuticle Sticks, of which the following is a specification.

This invention relates to a manicuring 10 implement, and more particularly to a cuticle stick or broach.

The primary object of the invention is to provide a cuticle stick having one end of wedge-shape adapted for introduction beneath the cuticle in a manner usual to such devices, and provided at a point slightly rearward of said end with one or more annular grooves designed for the reception of twisted or twirled-together fibers of an 20 absorbent cotton wrapping applied to said end, whereby said wrapping is retained in place.

It may here be explained that, as ordinarily used, a small wad of absorbent cotton is applied to the end of the stick in the form 25 of a loose wrapping and the same is then dipped in a liquid cleansing solution or anti-septic wash, ordinarily contained in a narrow neck bottle, after which it is applied to the cuticle. However, since no means has 30 been provided whereby such wrapping is secured in place, it frequently happens that the wrapping slips from the stick and is lost in the bottle.

As hereinbefore indicated, it is the aim of 35 the present invention to obviate the objectionable feature of former sticks, just referred to, by providing means for positively retaining the cotton wrapping in place.

In describing the invention in detail, reference is herein had to the accompanying 40 drawings, in which—

Figure 1 is a plan view of the invention;

Figure 2 is an edge view of the same;

Figure 3 is a view of the beveled end portion of the stick, showing a cotton wrapping applied thereto; and—

Figure 4 is a view illustrating a modification of the invention.

Referring to said drawings, 1 indicates the 50 body of the stick, which is preferably of cylindrical form in cross section. One end of said body may have the usual tapered

point 2, or it may have any other preferred shape. The opposite end of the stick has a head 3 of oppositely beveled wedge or chisel-like form presenting a sharp terminal edge. In the preferred construction, a reduced neck portion 4 is formed intermediate said head and said body by the provision of an annular channel or groove 5. Said neck is preferably of gradually tapered form and terminates at said head, which latter presents an annular rearwardly-facing shoulder 6. Said groove 5 is designed for the reception of the loose ends of the fibers of a cotton wrapping or swab 7 which is slipped over the head 3, said ends being drawn into said groove by a turning or twisting movement of the hand. So applied, the portion of the wrapping interengaged with the annular shoulder 6 effectively guards against chance detachment of the wrapping.

Instead of the single channel or groove 5 of the form mentioned, a plurality of closely adjacent shallow grooves 5^a, as illustrated in Fig. 4, may be provided, the same being designed to have fibers of the cotton wrapping drawn thereinto by a turning or twisting movement for binding such wrapping in place.

What is claimed is—

1. A cuticle stick comprising a body, and a chisel-like head at one end of said body, a reduced neck of tapered form being provided intermediate said head and said body, said head presenting a rearwardly-facing abrupt shoulder adapted to be engaged by twirled-together fibers of a cotton wrapping applied to said head.

2. A cuticle stick comprising a body having a beveled chisel-like end and provided with an annular groove adjacent to said end whereby is formed an annular rearwardly-facing shoulder, said groove being designed for the reception of twisted or twirled-together fibers of a cotton wrapping applied to said end, whereby said wrapping is retained in place on the latter.

In testimony whereof, I affix my signature in presence of the subscribing witness.

EARL W. KEYSER.

Witness:

H. E. DUNLAP.
